UNITED STATES PATENT OFFICE.

MAX PFAU, OF CHEMNITZ, GERMANY.

TYPEWRITING MACHINE.

Application filed January 16, 1922. Serial No. 529,616.

To all whom it may concern:

Be it known that I, MAX PFAU, a citizen of Germany, residing at Chemnitz, Germany, have invented certain new and useful 5 Improvements in Typewriting Machines; and I do hereby declare the following to be a full, clear, and exact description of the invention, such as will enable others skilled in the art to which it appertains to make and 10 use the same.

My invention relates to improvements in typewriting machines, and the object of the improvements is to provide a machine in which certain mechanism disposed internally of the 15 frame of the machine can readily be adjusted and repaired. With this object in view my invention consists in mounting such parts on a sectional frame which is removably secured to the main frame section, so that the 20 said parts can readily be dismounted and adjusted independently of the main frame section and the parts mounted thereon. In the practice of the invention I mount the universal bar and the parts controlled thereby 25 and preferably certain other parts such as the back spacing mechanism and the carriage spring and its housing on the subsidiary frame section. In the preferred form the said subsidiary frame section also 30 has the rear carriage supporting rail secured thereto, so that after dismounting the carriage and the subsidiary frame section access can be had to the inner parts of the machine.

In order that my invention be more clearly 35 understood an example embodying the same has been shown in the accompanying drawings, in which the same reference characters have been used in all the views to indicate corresponding parts. In said drawings,

40 Fig. 1, is a front view of the subsidiary frame section and the parts mounted thereon and showing in dotted lines a transverse section of the main frame section,

45 Fig. 2, is a side view of the subsidiary frame section and the parts mounted thereon, and showing in dotted lines the paper carriage, the platen, and parts of certain mechanisms mounted on the main frame section and cooperating with the parts mounted 50 on the subsidiary frame section,

55 Fig. 3, is a plan view of Fig. 1,

60 Fig. 4, is a side view of the rear part of

the main frame section and the subsidiary frame section with the mechanisms removed,

Fig. 5, is a vertical section taken on the 55 line 5—5 of Fig. 1,

Fig. 6, is a front view of the subsidiary frame section,

Fig. 7, is a vertical section taken on the 60 line 7—7 of Fig. 6, and

Fig. 8, is a side view of the main and subsidiary frame sections and the paper carriage and platen mounted thereon.

In describing the invention reference will be made to a typewriting machine of the 65 Underwood type. But I wish it to be understood that my invention is not limited to the use in connection with the type shown in the drawings.

In the example shown in the figures the 70 frame of the typewriting machine consists of a main section *a* having feet *a*¹ and a subsidiary section *b* secured to the upper rear part *a*² of the main section by means of screws *b*¹ or the like, the construction being 75 such that the subsidiary section with the mechanisms carried thereby can readily be mounted or dismounted for assembling and adjusting the said mechanisms independently of the main section of the frame. As 80 appears more particularly from Figs. 4 to 8, the subsidiary section consists of a horizontal portion *b*² generally of U-shaped cross-section, lateral arms *b*³, and arms *b*⁴ extending rearwards and upwards from the ends of 85 the arms *b*³. From the middle of the transverse part *b*² there depends a part *b*⁵ of rectangular form, and to the depending arms a pair of brackets *b*⁶ are secured which extend 90 therefrom forwards and towards the keyboard side of the machine. Laterally of the frame part *b*⁵ a Z-shaped bracket *b*⁷ is secured to the upper flange of the horizontal part *b*², which bracket is located at the front side of the part *b*² and extends therefrom 95 downwards. The upper flange of the part *b*² is curved upwards and downwards as at *b*¹⁰ to provide a housing for certain parts connected with the escapement mechanism, and near one of the ends of the part *b*² the 100 upper and lower flanges are enlarged at *b*¹¹ and the web is formed with a circular hole *b*¹² to accommodate the carriage spring and

105 its housing *k*.

On the subsidiary frame and its brackets the following mechanisms are mounted: To the arms b^4 the rear guide rail c^1 for the paper carriage c is secured by means of 5 screws c^2 . The platen c^3 and the paper carriage c have been shown in Fig. 2 in dotted lines. The bracket b^6 provides a support for the universal bar d which as shown 10 is secured to a horizontal U-shaped frame d^1 guided with horizontal slots d^2 on pins d^3 secured to the front ends of the arms b^6 and jointed at its rear end to arms d^4 of a rocker d^5 mounted on a shaft d^6 secured to the arms b^6 . A spring d^7 secured with one 15 end to a hook d^8 connected with said rocker and with the opposite end to a lug d^9 provided at the front end of the arm b^6 tends to push the rocker d^5 and the universal bar d forwards.

20 The universal bar is adapted to be reciprocated by the type levers f shown in Fig. 2 in dotted lines, as is known in the art.

To the rocker d^5 a lever e is secured which takes part in the rocking movement imparted to the rocker by the type levers acting on the universal bar, and transmits such rocking movement through the intermediary of a lever e^1 and a connecting rod e^2 jointed thereto to the ribbon feed mechanism (not 30 shown).

On the portion b^{10} of the frame part b^2 the escapement wheel g , the clutch g^1 and the gear wheel g^2 cooperating with the usual carriage rack (not shown) are mounted, and 35 at the rear side of the part the carriage brake disk g^3 is provided.

The movement of the escapement wheel g is controlled in the usual way by escapement pawls g^4 , g^5 mounted on a carrier g^6 40 having a rocking support between pointed screws g^7 screwing in eyes g^8 of the bracket b^6 . The rocking carrier g^6 is acted upon by the universal bar through the intermediary of a slide g^{10} transversely shiftable on a pair 45 of transverse rods g^{11} and g^{12} of the frame d^1 and carrying an adjustable plate g^{13} . Furthermore, the carrier g^6 is adapted to be operated independently of the universal bar from the spacing key acting through the 50 intermediary of a lever g^{14} and an arm g^{15} secured to the carrier.

The slide g^{10} is adapted to be shifted transversely of the frame d^1 by means of a rod h guided longitudinally of the frame section b and engaging an arm h^1 of the slide g^{10} , and such movement is imparted to the slide for throwing the ribbon vibrator into or out of operation. As shown a slotted plate h^2 is secured to the slide which is adapted to engage a pin h^3 secured to an arm h^4 of a lever h^5 connected with the ribbon vibrator (not shown).

On the arm b^7 the back spacing mechanism is mounted which as shown consists of a lever 65 i rockingly mounted at i^1 and carrying a

dog i^2 , and an operating lever i^3 likewise mounted at i^1 and jointed with its upper end to the dog i^2 . The lever i^3 is loosely connected with the back spacing mechanism (not shown). 70

If it is desired to dismount the subsidiary frame and the parts mounted thereon, I disconnect the ribbon vibrator from the slotted plate h^2 by means of the rod h , and I remove the screws b^1 . 75

The parts mounted on the main frame of the machine are in loose engagement with the parts mounted on the subsidiary frame. Therefore, when mounting the subsidiary frame on the main frame it is necessary only 80 to throw the parts h^2 and h^3 into engagement with each other, whereupon the machine is ready for use.

While in describing the invention reference has been made to a particular example 85 embodying the same, I wish it to be understood that my invention is not limited to the construction shown in the drawings, and that various changes may be made in the general arrangement of the apparatus and 90 the construction of its parts without departing from the invention.

I claim:

1. In a typewriting machine, the combination, with a main frame section, and a subsidiary frame section removably connected therewith, of the type levers and type lever operating mechanism both mounted on the main section, and the universal bar and escapement mechanism both mounted on the subsidiary frame section. 95

2. In a typewriting machine, the combination, with a main frame section, and a subsidiary frame section removably connected therewith, of the type levers, type lever operating mechanism, and a spacing key lever all mounted on the main section, and the universal bar and escapement mechanism both mounted on the subsidiary frame section, said escapement mechanism comprising 100 an operating member adapted to be operated by said spacing key lever and independent of the universal bar. 105

3. In a typewriting machine, the combination, with a main frame section, and a subsidiary frame section removably connected therewith, of the type levers, type lever mechanism, and a spacing key lever all mounted on the main frame section, and the universal bar and escapement mechanism both mounted on the subsidiary frame section, said escapement mechanism comprising an operating member in loose operative engagement with said spacing key lever and independent of the universal bar. 115

4. In a typewriting machine, the combination, with a main frame section, and a subsidiary frame section removably connected therewith, of the type levers, type lever operating mechanism, ribbon spools, ribbon feed 120

130

mechanism, and ribbon vibrator all mounted on said main frame section, and the universal bar, operating means for the ribbon feed mechanism, and operating means for the vibrator mounted on the subsidiary frame section.

5. In a typewriting machine, the combination, with a main frame section, and a subsidiary frame section removably connected therewith, of the type levers, type lever operating mechanism, ribbon spools, ribbon feed mechanism, and ribbon vibrator all mounted on said main frame section, the universal bar operating means for the ribbon feed mechanism and operating means for the vibrator mounted on the subsidiary frame section, and means to disconnect said vibrator from the operating means therefore, said ribbon feed mechanism and its operating means being in loose engagement with each other.

6. In a typewriting machine, the combination, with a main frame section, and a subsidiary frame section removably connected therewith, of the type levers, type lever operating mechanism, and operating means for the back spacing means all mounted on the main frame section, and the universal bar, escapement mechanism, and back spacing mechanism all mounted on the subsidiary frame section, said back spacing mechanism and its operating means being in loose engagement with each other.

7. In a typewriting machine, the combination, with a main frame section, and a subsidiary frame section removably connected therewith, of the type levers and type lever mechanism both mounted on the main frame section, and a rear carriage supporting rail, the universal bar and escapement mechanism all mounted on the subsidiary frame section, the front carriage supporting rail being mounted on the main frame section.

8. In a typewriting machine, the combination, with a main frame section, and a subsidiary frame section removably connected therewith and exclusively supported there-

on, of the type levers and type lever mechanism mounted on the main frame section, and the universal bar and escapement mechanism mounted on the subsidiary frame section.

9. In a typewriting machine, the combination, with a main frame section, and a subsidiary frame section substantially in the form of a bar and removably connected exclusively to the upper rear part of said main frame section, of the type levers and type lever mechanism mounted on the main frame section, and the universal bar and escapement mechanism mounted on the subsidiary frame section.

10. In a typewriting machine, the combination, with a main frame section comprising a base portion, upright corner pieces and integral longitudinal portions connecting the corner pieces at their top parts, and a subsidiary frame section substantially in the form of a bar and removably connected exclusively to the upper rear part of said main frame section, of the type levers and type lever mechanism mounted on the main section, and the universal bar and escapement mechanism mounted on the subsidiary frame section.

11. In a typewriting machine, the combination, with a main frame section, and a subsidiary frame section substantially in the form of a bar formed with a depending portion and removably connected exclusively to the upper rear part of said main frame section of the type levers and type lever mechanism mounted on the main section, brackets secured to said depending portion and projecting forwardly therefrom, the universal bar mounted on said brackets, and escapement mechanism mounted on said brackets and subsidiary frame section.

In testimony whereof I hereunto affix my signature in the presence of two witnesses.

MAX PFAU.
